UNITED STATES PATENT OFFICE.

BOTHO SCHWERIN, OF FRANKFORT-ON-THE-MAIN, GERMANY, ASSIGNOR TO ELEKTRO-OSMOSE AKTIENGESELLSCHAFT (GRAF SCHWERIN GESELLSCHAFT), OF FRANKFORT-ON-THE-MAIN, GERMANY, A CORPORATION.

METHOD FOR SEPARATION OF FINELY-DIVIDED SUBSTANCES FROM COARSE AND FOREIGN MATTERS.

1,230,524.

Specification of Letters Patent. Patented June 19, 1917.

Application filed May 13, 1915. Serial No. 27,888.

To all whom it may concern:

Be it known that I, BOTHO SCHWERIN, residing at Frankfort-on-the-Main, Germany, have invented certain new and useful

5 Improvements in Methods for Separation of Finely-Divided Substances from Coarse and Foreign Matters, of which the following is a specification.

My invention relates to improvements in 10 a method for separating substances in suspension. It is known, that finely divided substances may be separated from coarse and foreign matters which are in suspension in a liquid by adding suitable electrolytes to 15 the liquid containing such substances. By additions of this kind one component part is brought into the sol-state and is held in suspension. The coarse, foreign and oppositely charged parts are deposited in gel- 20 state or, according to their nature and their electrical charge, are brought into a sol-state less complete or strong than that aforesaid.

After the precipitation of the coarse, oppositely charged and indifferent matters, also 25 a fractionation of the finely divided substances held in sol-state occurs. This fractionation is performed according to the size of the particles since the coarser particles 30 oscillate more feebly than and precipitate before the finer particles.

In the accompanying drawing there is illustrated, more or less diagrammatically an apparatus adapted for carrying out the 35 hereinbefore described method.

Referring to the drawing 1 designates the body of the centrifuge which is supported on a shaft 2 mounted in suitable bearings 4, 5. The bearing 5 is shown fixed on a base 7 40 while the bearing 4 is carried by a yoke-like frame 6 rising from said base. Power is communicated to the shaft 2 by a band 3.

The electric current is supplied by a dynamo 11, one of the brushes of which is connected with a terminal 10 on a pole piece 8 that extends into the liquid in the receptacle 1 while the other brush is connected with a contact 9 that bears against a collar on the shaft 2.

I have now found, that by subjecting such mixtures in suspension to the action of centrifugal force the separation is accelerated and the fractionation more strongly marked. The centrifugal movement may be effected in various ways. The liquid may be centrifuged in a closed centrifuge, whereby the liquid rotates with the centrifuge. The indifferent and coarse particles being in gel-condition are deposited at the partition of the centrifuge vessel, whereas the fine and highly charged particles remain in suspension and only deposited after a length of time depending upon their electrical condition or charge and oscillation. The centrifugal movement may further be produced by causing the liquid to rotate in a cylindrical vessel.

It is known, that the component parts of a suspension mixture which are in sol-condition may be recovered by the action of electro-osmosis. This process may be used in combination with the described centrifugal method. To this end the centrifuge or the vessel containing the liquid is connected with one pole of the source of electricity, the other pole being immersed in the liquid.

What I claim is:

1. The herein described method of separating substances in suspension in a liquid comprising adding a suitable electrolyte to the liquid and subjecting the liquid and the substance in sol-state therein to the action of centrifugal force.

2. The herein described method of separating substances in suspension in a liquid comprising adding a suitable electrolyte to the liquid and subjecting the liquid and the substance in sol-state therein to the simultaneous action of centrifugal force and an electric current.

In testimony whereof I affix my signature in presence of two witnesses.

BOTHO SCHWERIN.
